UNITED STATES PATENT OFFICE.

JAMES GRANGER POE, OF DALLAS, TEXAS.

DESIGN FOR A SYRINGE-NOZZLE.

SPECIFICATION forming part of Design No. 34,664, dated June 18, 1901.

Application filed May 16, 1901. Serial No. 60,616. Term of patent 14 years.

To all whom it may concern:

Be it known that I, JAMES GRANGER POE, a citizen of the United States, residing at Dallas, in the county of Dallas and State of Texas, have invented and produced a certain new and original Design for a Syringe-Nozzle; and I do hereby declare the following to be a full, clear, and exact description of the invention, such as will enable others skilled in the art to 5 which it appertains to make and use the same.

My invention relates to a new and original design for a syringe-nozzle; and the design consists of the essential characteristics hereinafter more specifically described, and substantially as shown in the accompanying 15 drawings, in which—

Figure 1 is a side elevation of the device; Fig. 2, an end view; Fig. 3, a section along the line 3 3 of Figs. 2 and 4, and Fig. 4 a 20 front view.

The leading feature of my design consists in the peculiar shape of the implement, in which the shank B terminates in the flaring shield A, which is curved longitudinally, as at a, and transversely, as at a'. The shank B 25 is perforated with the larger duct D and the smaller duct E, with the lateral openings d and e, and in front of the shield are the two nipples C and C', curved inward, as at c and c', respectively.

What I claim is—

The design for a syringe-nozzle, substantially as herein shown and described.

In testimony whereof I affix my signature in presence of two witnesses.

JAMES GRANGER POE.
